C. T. DUNKLAU

MUSICAL INSTRUMENT STAND

Filed Nov. 22, 1924

INVENTOR.
CASPER THEODORE DUNKLAU
BY Munn & Co.
ATTORNEYS.

UNITED STATES PATENT OFFICE.

CASPER THEODORE DUNKLAU, OF LOS ANGELES, CALIFORNIA.

MUSICAL-INSTRUMENT STAND.

Application filed November 22, 1924. Serial No. 751,587.

My invention relates to and has for its purpose the provision of a collapsible stand, particularly adapted, although not necessarily, for supporting musical instruments, such as banjos, guitars, and the like, during rest periods or when the instrument is not in use and in such manner as to prevent it being accidentally knocked over or stepped upon.

It is also a purpose of my invention to provide a collapsible stand of the above described character which, aside from being ornamental and pleasing in appearance, is extremely light and substantial in construction; a stand which can be readily collapsed so as to occupy a minimum space to permit of its being conveniently carried in the hand; and a stand in which the elements thereof are so constructed as to permit of their being manufactured at a relatively low cost.

I will describe only one form of musical instrument stand embodying my invention, and will point out the novel features thereof in claims.

In the drawings

Figure 1 is a view showing in side elevation, and partly in section, one form of stand embodying my invention in supported position with respect to a banjo;

Figure 2 is a view showing in front elevation the stand shown in Figure 1, and taken on the line 2—2 of Figure 1;

Figure 3 is a fragmentary sectional view taken on the line 3—3 of Figure 1;

Figure 4 is a fragmentary vertical sectional view taken on the line 4—4 of Figure 1;

Figure 5 is an enlarged fragmentary view showing in front elevation the connections for certain of the elements with respect to one of the legs of the stand;

Figure 6 is a horizontal sectional view taken on the line 6—6 of Figure 2.

Similar reference characters refer to similar parts in each of the several views of the drawings.

Referring specifically to the drawings, my invention in its present embodiment comprises generally a tripod designated at T, and from the upper end of which extends a bracket B adapted to receive and support the neck of an instrument placed thereon, the body of the instrument being supported by a hammock H spanning two of the legs of the tripod.

The tripod T comprises a pair of legs 15 and 16 which are formed of angle bars and pivotally connected to each other at their upper ends by means of a bolt 17 provided with a wing nut 17^a adapted to engage a clevis 18. The bracket B includes an arm 19 made up of a single length of wire bent upon itself to provide parallel portions, the free ends of the portions being bent laterally and forwardly to provide spaced arms 20, and the parallel portions and arms being held in fixed relation by means of a metallic sleeve 21. The other leg of the tripod T is designated at 22, and consists of a rod bent at its upper end to provide a loop 23 defining a slot 23^a through which the bolt 17 is extended, the lower end of the arm 19 also receiving the bolt and the two being disposed within the clevis 18 as clearly illustrated in Figure 3, so that when the nut 17^a is fed inwardly, the clevis will co-operate with the upper ends of the legs 15 and 16 to securely clamp the several elements together and thus firmly hold the stand in the position illustrated in Figures 1 and 2. It will be noted that the association of the bracket B with respect to the tripod is such that by manipulation of the lug 17^a the bracket can be adjusted vertically to vary the position of the arms 20 so as to accommodate the bracket to instruments having necks of different lengths. Further, the loop 23 of the leg 22 is sufficiently elongated to allow the limited adjustment of the leg so as to vary the inclination of the legs 15 and 16.

The hammock H is formed of flexible material, such as felt or the like, and is secured at its ends to the legs 15 and 16 through the medium of brackets 25 and 26 made from short lengths of angle bars and secured to the legs 15 and 16, respectively, through rivets 27 and washers 28 arranged so as to allow pivotal movement of the brackets on the rivets so that the former can occupy positions at right angles to the legs 15 and 16 or positions parallel to the legs. As illustrated to advantage in Figure 5, each end of the hammock H is secured to one bracket 25—26 or the other by a spring clip 29, the end of the apron being trained about the clip between the latter and the bracket, as clearly illustrated.

In order to maintain the legs 15 and 16 in definite divergent relation, I have provided a spreader bar 30 pivoted at one end on the bracket 25, as indicated at 31, and extending into a suitable opening in the other bracket

26 so as to permit removal thereof when collapsing the stand.

To prevent the body of an instrument supported on the stand from contacting with the legs 15 and 16 and thus possibly marring the body, I have provided a bar 32 pivoted to the leg 15, as indicated at 33, and having its free end engaging between a lip 34 and the leg 16, the lip being formed by splitting and 10 out-striking a portion of the leg. This bar 32 is covered with a sleeve 35 formed of felt or other suitable material, and against which the body of the instrument is adapted to repose when supported by the hammock H, 15 thus preventing the body from contacting with the legs 15 and 16.

In practice, the body of the instrument to be supported is placed within the hammock H, as clearly illustrated in Figure 1, so that 20 the neck of the instrument rests upon the bracket B and between the arms 20, the position of the arms 20 preventing undue lateral movement of the neck, as will be understood. It is to be particularly noted that the bracket 25 B is inclined upwardly or forwardly with respect to the plane of the legs 15 and 16 so that the point at which the neck of the instrument contacts with the bracket is such as to support the body of the instrument in 30 slightly spaced relation to the legs 15 and 16.

When it is desired to collapse the stand, it will be clear that by loosening the nut 17^a and then swinging the spreader rod 30 and the bar 32 to a position substantially parallel with respect to the leg 15, the entire stand can be completely collapsed. With the loosening of the nut 17^a the bracket B can be slid downwardly between the legs 15 and 16. The rear leg 22 is moved upwardly 40 so that the bolt 17 rests in the lower part of the loop 23, when the leg can be folded into parallel position with respect to the other leg. The brackets 25 and 26 can be swung into 45 position parallel with respect to the legs 15 and 16 while the hammock, being formed of flexible material, will easily fold around the entire assembly.

Although I have herein shown and described only one form of musical instrument 50 stands embodying my invention, it is to be understood that various changes and modifications may be made herein without departing from the spirit of the invention and the spirit and scope of the appended claims.

55 I claim:

1. A stand of the character described comprising a tripod, a spanner member detachably connecting two of the legs of the tripod to maintain the legs in angular relation, a hammock spanning said legs, a protecting bar pivoted on one of the legs and detachably connected to the other leg, and a bracket ex-

tending upwardly from the tripod and telescopically associated therewith to permit folding of the bracket on the tripod. 65

2. A stand of the character described comprising a tripod, a bracket extending upwardly from and adjustable on the tripod, brackets pivoted on two of and extending laterally from the legs of the tripod, and a flexible 70 hammock connected at its ends to said brackets so as to be disposed to one side of said legs.

3. A stand of the character described comprising a tripod, a bracket extending upwardly from and foldable on the tripod, brackets pivoted on certain of the legs, a spreader bar pivoted on one of the brackets and detachably engaging the other bracket, and a hammock connecting the brackets. 75

4. A stand of the character described comprising a tripod, means for pivotally connecting the legs of the tripod, means for clamping the legs together, one of said legs having an angularly disposed portion at its pivoted 80 end and slotted to receive the first means to thereby permit sliding movement of the leg on the first means to occupy a parallel or angular position with respect to the other legs, a bracket supported on the legs at their point of connection, and a hammock connecting certain of the legs. 90

5. A stand of the character described comprising a tripod, including a pair of legs and a third leg having at one end an angularly 95 disposed portion provided with a slot extending into the remaining portion, a bracket, means for pivotally connecting the legs and bracket and comprising a threaded stud extending through the pair of legs, bracket and 100 said slot of the third leg, a clamping nut on said stud, said slot permitting sliding movement of the third leg on said stud to occupy a parallel or angular position with respect to the pair of legs, said nut operating to 105 clamp the third leg in said positions and the legs and bracket against relative movement, and a hammock connecting certain of the legs.

6. The combination as embodied in claim 110 5 wherein a clevis is mounted on said stud and operates when the nut is in clamping position to prevent relative rotation of the third leg and bracket.

7. A stand of the character described comprising a tripod, the legs of which are pivotally connected to each other, one of said legs having an angularly disposed end portion and being slotted to allow sliding movement thereof to occupy a parallel or an angular position with respect to the other legs, 115 a bracket supported on the legs, and a hammock connecting certain of the legs. 120
